UNITED STATES PATENT OFFICE.

FRED EVANS, OF SUMMIT, NEW JERSEY, ASSIGNEE, BY MESNE ASSIGNMENTS, TO
VOICES INCORPORATED, A CORPORATION OF DELAWARE.

TALKING-TOY MECHANISM.

Application filed March 21, 1923, Serial No. 626,493. Renewed July 7, 1925.

To all whom it may concern:

Be it known that I, FRED EVANS, a citizen of the United States, residing at Summit, county of Union, and State of New Jersey, have invented certain new and useful Improvements in a Talking-Toy Mechanism, of which the following is a specification.

This invention relates to improvements in toys, and more specifically to sounding devices to be used in so-called "talking toys".

One object of this invention is to provide a sounding device for dolls, or other toys of that character, so designed as to produce a continuous sound in accordance with certain movements of the body of the doll.

Another object of the invention is to provide a simple, effective means by which a voice for so-called talking toys may be produced, this voice being of such design that it will produce a relatively continuous sound as the body of the doll is moved.

25 Other objects and aims of the invention, more or less specific than those referred to above, will be in part obvious and in part pointed out in the course of the following description of the elements, combinations arrangements of parts and applications of principles, constituting the invention; and the scope of protection contemplated will be indicated in the appended claims.

In the accompanying drawing, wherein I have shown a preferred form of embodiment of my invention:

Figure 1 is a view in side elevation of the device, certain parts being broken away so as to show the construction; and

Figure 2 is an end view of the device shown in Figure 1.

Referring now to the drawing, wherein similar reference characters refer to similar parts in both views thereof, the reference character 1 designates a cylindrical container constructed preferably of board, or cardboard, fibre, or other light cheap material. This device is provided with a head indicated in dotted lines at 2, to which is at-

tached a guide rod 3, extending from the head 2 to a second head 4, mounted in the cylindrical body at a slight distance from one margin. 50

Mounted within the body 1, and between the heads is a collapsible bellows 5, constructed of treated fabric, or other similar material of that character, which is comparatively air proof, this bellows being attached to the head 4 by any suitable means, here shown as a ring 6. At its upper end the bellows 5 is attached to a weighted head 7, indicated in dotted lines, at the upper end of the container 1, and this head having an aperture through which the guide rod 3 passes. The head 4 is provided with a pair of orifices 8 and 9, the orifice 8 opening into a sound box 10 provided with a reed 11, the orifice 9 opening into a similar sound box 12, which communicates with the atmosphere through a reed box 13. The orifice 9 has mounted so as to overlie it, a flap valve 14, so arranged as to permit air to pass into the interior of the bellows through the orifice 9, but to prevent air passing outwardly through orifice 9 from the bellows. The action of the voice is as follows:

When the device is moved to the position indicated in Figure 1, the weight 7 will naturally move downwardly, collapsing the bellows and forcing air outwardly through the orifice 8 into the chamber 10, thence to 80 the atmosphere, through the reed box 11. This will give a sound, the character of which may be determined by the selection of the reed. When the device is moved to the reverse position, the weight 7 will move 85 outwardly, being guided along the rod 3, and in its outward movement the bellows will expand and air will be drawn there-through.

In the case of the collapse of the bellows, 90 the flap valve 14 will be drawn down so as to close the orifice 9, whereupon no air will be permitted to pass thereinto. In the reverse movement, however, the bellows opening, air 95 will be drawn through the reed box 13 into the chamber 12, thence into the interior of

the bellows, through the orifice 9, and the flap valve 14, which is displaced from its seat. Air will also pass inwardly through the reed box 11, chamber 10, and orifice 8, but by reason of the way the reed is positioned, the reed 11 in the case of the intake will give no sound.

It will be seen, therefore, that when the device is in the position shown in Figure 1, the collapse of the bellows will sound the reed 11, and when the position of the device is reversed, the reed 13 will sound. These reeds may be so designed as to give a similar sound, or may, if desired, give sounds of different tone and intensity.

The device may be readily mounted within the body of a doll, or other toy of that character, and when the position of the doll is reversed, the movement of the weight causing the collapse or expansion of the bellows, will produce the sound.

It will be seen that the device is simple in construction, and has no parts that may readily get out of order. The sounds produced will be clear and distinct, and the device will have a long life under the rough usage to which such devices are ordinarily subjected.

As many changes could be made in this construction without departing from the scope of the following claims, it is intended that all matter contained in the above description or shown in the accompanying drawing shall be interpreted as illustrative only and not in a limiting sense.

Having thus described my invention what I claim as new and desire to secure by Letters Patent is:

1. In a talking toy mechanism, the combination with a container, of a head fixed therein, a bellows attached to the said head, a weight borne by the movable end of the bellows, a rod having one end secured centrally to the said head and extending axially through the bellows and through the said weight as a guide for the said weight, and said head having a plurality of orifices extending through it, separate reed chambers arranged to cover the said orifices, reeds in communication with the said chambers and with the atmosphere, and one of the said orifices being controlled by a valve carried by the said head.

2. In a talking toy mechanism, the combination with a container, of a head fixed therein, a bellows attached to the said head, a weight borne by the movable end of the bellows, a rod having one end secured centrally to the said head and extending axially through the bellows and through the said weight as a guide for the weight, the said head having a plurality of orifices extending through it, separate reed chambers arranged to cover the said orifices, reeds in communication with the said chambers and

with the atmosphere, and one of the said orifices being controlled by a valve carried by the said head and opening inwardly admitting air from one of the reed chambers into the bellows.

70

3. A sounding device having in combination a tubular casing, a tubular bellows having one of its heads fixed with respect to the casing and its other head free to move longitudinally of the casing, the freely movable head being weighted whereby it will compress and expand the bellows by gravity, one of said heads having a plurality of orifices therethrough, a reed pipe associated with one of said orifices and adapted to sound when air is forced out of the bellows, and a reed pipe associated with the other orifice and adapted to sound when air is drawn into the bellows.

75

4. A sounding device having in combination a tubular casing, a tubular bellows having one of its heads fixed with respect to the casing and its other head free to move longitudinally of the casing, the freely movable head being weighted whereby it will compress and expand the bellows by gravity, one of said heads having a plurality of orifices therethrough, a reed associated with one of said orifices and adapted to sound when air is forced out of the bellows, and a reed associated with the other orifice and adapted to sound when air is drawn into the bellows.

80

5. A sounding device having in combination a tubular casing, a tubular bellows having one of its heads fixed with respect to the casing and its other head free to move longitudinally of the casing, the freely movable head being weighted whereby it will compress and expand the bellows by gravity, a guide rod fixed with respect to the casing, for guiding said movable head in its movement back and forth in the casing, one of said heads having two orifices therethrough, sound chambers covering said orifices respectively, reed pipes inserted in said sound chambers respectively, one being adapted to sound when air is forced out of the bellows and the other being adapted to sound when air is drawn into the bellows.

85

6. A sounding device having in combination a tubular casing, a tubular bellows having one of its heads fixed with respect to the casing and its other head free to move longitudinally of the casing, the freely movable head being weighted whereby it will compress and expand the bellows by gravity, one of said heads having two orifices therethrough, sound chambers covering said orifices respectively, reed pipes inserted in said sound chambers respectively, one being adapted to sound when air is forced out of the bellows and the other being adapted to sound when air is drawn into the bellows.

90

7. A sounding device having in combination a tubular casing, a tubular bellows having one of its heads fixed with respect to the casing and its other head free to move longitudinally of the casing, the freely movable head being weighted whereby it will compress and expand the bellows by gravity, one of said heads having two orifices therethrough, sound chambers covering said orifices respectively, reed pipes inserted in said sound chambers respectively, one being adapted to sound when air is forced out of the bellows and the other being adapted to

sound when air is drawn into the bellows, and a valve for closing said last mentioned orifice when the bellows is being compressed.

7. A sounding device having in combination a tubular casing, a tubular bellows having one of its heads fixed with respect to the casing and its other head free to move back and forth in the casing, the freely movable head being weighted whereby it will ¹⁵ 10 press and expand the bellows by gravity,

said fixed head having two orifices there-through, a reed pipe associated with one of said orifices and adapted to sound when air is forced out of the bellows and a reed pipe associated with the other orifice and adapted to sound when air is drawn into the bellows.

In testimony whereof, I affix my signature.

FRED EVANS.
